In Italy April 19, 1934

15 Claims. (Cl. 133—2)

This invention has for its object an automatic apparatus for computing and delivering the change between a tendered money and an amount to be collected; the apparatus of this invention may be used by itself as a change computing and delivering apparatus or as a unit embodied in a cash register or a similar machine.

The apparatus of this invention comprises change coin distributors, means for actuating them, means for setting the amount to be collected on setting means which separately correspond with the numerical orders or ordinal places of the several figures providing said amount, and means driving said actuating means in accordance with the conditions of said setting means, as well as selective setting means operable in accordance with the tendered money and operative on said distributor actuating means to put them in conditions of operation in accordance with such tendered money with respect to which the change over said amount to be collected must be computed and delivered.

Owing to its organization and operation, the apparatus of this invention is very simple while being able to operate in respect of any desired amount to be collected and tendered money within the ranges for which the apparatus is devised and embodied.

This apparatus is particularly proper for its embodiment in cash registers and the like in which the amount to be collected is decomposed by manipulation of setting-in keys in figures pertaining to subsequent numerical orders.

The apparatus of this invention includes further new and useful features hereinafter described.

A construction of an apparatus according to this invention as embodied in a key operated cash register is illustrated by way of example on the annexed drawings in which

Figure 1 is a transverse section of a key operated cash register having the apparatus of this invention embodied therein, said section being made on line 1—1 of Figure 2;

Figure 2 is in its bottom part a plan view of parts located under the figure setting quadrants of said cash register and in its top part a horizontal section on line 2—2 of Figure 1.

Figure 3 is the diagram of the keyboard of the cash register with the diagrammatic illustration of the cooperating cam members of the apparatus.

Figure 4 is a diagrammatic section on line 4—4 of Figure 5 with the setting mechanism and other parts removed and some parts shifted with respect

to their position in Fig. 1 this figure also illustrating the actuation of the change coin distributors;

Figure 5 is in part a section of change coin distributors on line 5—5 of Figure 4 and in part a plan view of parts shown in Figure 4.

Figure 6 is a partial vertical section on line 6—6 of Fig. 4;

Figure 7 is a side view of a separate distributor as seen in a direction perpendicular to Figure 6 and on the opposite side with respect to Figure 4.

Figure 8 illustrates the transfer gear intended to control the operative conditions of parts actuating the change coin distributors, such gear being shown in detail and in section on line 8—8 of Figure 9;

Figure 9 is a plan view of Figure 8, with parts in section;

Figure 10 is a fragmentary section on line 10—10 of Figure 8;

Figure 11 is a fragmentary view showing separately a detail of Figure 9;

Figure 12 is a diagrammatical and fragmentary view substantially on line 12—12 of Fig. 1, showing the actuating means for the figure setting quadrants of said cash register.

In the embodiment illustrated on the annexed drawings and hereinafter described by way of example, the change computing and distributing device of this invention is embodied in a key-operated cash register of well known construction comprising, for each numerical order of figures providing the amount to be cashed or collected, a setting member or quadrant adapted to be shifted through predetermined angles under the control of selectively manipulated setting keys and under the actuation of the main shaft of the register. The apparatus of this invention may also be embodied in lever-operated cash registers in which each setting member or quadrant is actuated directly or indirectly by a lever or handle, as well as in cash registers of both key- and handle-type in which said setting members are arranged for rectilinear operation through different extents instead of for oscillation through different angles.

As an illustration of this class of registers reference is made to British Patents Nos. 5,238/1891, 18,079/1892, 9,400/1897, U. S. Patent No. 580,378, French Patents Nos. 551,417, 616,322.

In the present specification, only the parts of a conventional cash register which cooperate with the apparatus of this invention are illustrated and described, such parts comprising for each numerical order or ordinal place (that is for units, 55

tens, hundreds and so on as well for tenths and hundredths respectively) a figure setting gear including a quadrant 1 loose on a transverse shaft 2 and having teeth 3 which actuate devices belonging to conventional cash registers. Said devices are shown diagrammatically by 4 in respect of an indicating device, by 5 in respect of driving shafts actuating a printing device and by 6 as a totalizing device, these parts being popular in the art and having no interest in this invention.

On each quadrant 1 a radial rod 9 is mounted to move by means of two links 7 fulcrumed on said quadrant at 8 and providing a four bar linkage, the outer end of said rod 9 being thus able to engage any of notches 10 of a stationary plate 11 fast on the bed frame 12 of the cash register. The rod 9 has at its internal end a tooth 13 able to engage a tooth 14 of a driving quadrant 15 solid with shaft 2, this shaft being oscillated, at a proper time during the register operation, by means of arm 16 and bar 17, these parts being actuated in turn by an arm 122 (Figures 2 and 12) loose on spindle 35 and by a cam 120 and a counter-cam 121 fast with the main cam shaft 28 of the register.

As shown in Figures 2 and 12, said main shaft 28 is driven by a handle 108 by the intermediate of pinions 109 and 110 to make two complete revolutions at each operation, the handle 108 being actuated by the operator to move through one complete revolution at each operation.

An arm 19 fulcrumed at 20 on quadrant 1 is pivotally connected at 18 with rod 9 and the head 19' of said arm 19 is operated by a return spring 21 acting to move rod 9 towards quadrant 15.

As conventional, a row of keys 25 cooperating with quadrant 1 is arranged around said quadrant, they being mounted to reciprocate radially in stationary plate 11.

On arm 19 is fulcrumed at 22 a pawl 23 having a return spring 24 and acting on arm 19, 19', said pawl 23 on impinging against the one of keys 25 which has been manipulated, causing the arm 19 to rock in opposition to spring 21 and to shift the rod 9 radially outward to carry it into engagement with one of notches 10 of stationary plate 11. As understood and conventional, the keys 25 above referred to cooperate with the quadrant 1 for positioning it in accordance with the figure to be set in its ordinal place or numerical order and the end of that of said keys 25 which has been manipulated in said row extends in the path of pawl 23 during the oscillation of quadrant 1 carrying it.

Abutments 26 of driving quadrants 15 operate to return respective quadrants 1 in their zero position in which their pawls 23 are engaged with a stop 27 which is released automatically when a key 25 representing a significant figure is manipulated in the respective order. This operation is effected by a conventional device of the kind illustrated in Fig. 4 of French Patent No. 551,417 whose pawl 35 corresponds with stop 27 of the present application.

In the operation of the cash register as a whole, as conventional and well known in the art, after keys 25 have been manipulated in the several ordinal places, the main cam shaft 28 which carries out the register operation is actuated and it causes the shaft 2 and driving quadrants 15 to oscillate firstly in anti-clockwise direction and then in clockwise direction, this actuation being effected by cams 120, 121 of shaft 28,

lever 122, bar 17 and arm 16 as hereinbefore described. In said anticlockwise oscillation the abutments 26 of driving quadrants 15 carry all quadrants 1 in their illustrated zero-position while at the beginning of the second or clockwise oscillation in all the quadrants 1 in respect of which a key 25 has been manipulated and stop 27 has been removed, the respective arm 19 under the action of spring 21 carries rod 9 with its tooth 13 into engagement with tooth 14 of driving quadrant 15. During this clockwise oscillation said driving quadrant 15 drives the respective quadrant 1 by the intermediary of teeth 14, 13 and rod 9 until the respective pawl 23 engages the end of the key 25 which has been manipulated in the respective row; then the rod 9 is shifted radially outward to release quadrant 15 and engage the respective notch 10 of stationary plate 11. Thus the quadrant 1 is stopped after it has been moved through an angle corresponding with the figure or numerical value affixed to the key 25 which has been manipulated in the respective row.

As above intimated a quadrant 1 and a row of keys 25 with cooperating parts are provided in respect of each ordinal place of the item or amount to be set in by the manipulation of keys of several rows, and all said quadrants 1 are operated in the described manner by the actuation of cam shaft 28 to reproduce by the several angles they have moved through the amount or item set in by the manipulation of keys 25 in several rows.

In accordance with this invention the described operation in respect of each numerical order or ordinal place of the figures of the amount to be cashed, of a separate gear comprising setting members as keys 25 and a member as quadrant 1 which in the register operation moves through a defined space depending upon the particular figure set in the respective order, is availed of to set control means for change delivery. These control means include in each numerical order a cooperating member devoted to change distribution and which in turn presets the operation of change coin distributors and shares thereon the correct change on the basis of the monetary system to which the apparatus is devoted, while the actuation of said distributors is effected in the subsequent operation. Further the change coin distributor operation is made under the selective control of a further setting device (referred to in its whole in the claims as "denomination means") which is preset, by a manipulation similar to the usual ones in cash registers, in accordance with the tendered money with respect to which the change is to be delivered, said last named setting device releasing from operation those of said distributors which must remain inoperative on account of the value of the tendered money.

As above stated in the embodiment of this invention as described and illustrated by way of example, it is assumed that the cash register includes four rows of cash setting keys 25.1, 25.2, 25.3, 25.4 corresponding with tens, units, tenths and hundredths respectively, each of said key rows cooperating with a quadrant as 1. Further the apparatus includes a row of keys 57 for setting the tendered money and a cooperating quadrant R.1 which is controlled and actuated in the manner hereinbefore described with respect to one of quadrants 1.

In the embodiment of this invention in a handle-manipulated cash register, handles each 75

actuating a cooperating quadrant 1, 1.R are substituted for rows of keys 25 and 57.

The change delivering device (Figures 1, 2, 4, 5) includes a stationary spindle or stub shaft 29 extending parallel with shaft 2 of quadrants 1. A cam member 30, 31, 32, 33 is loose on said spindle 29 in respect of each quadrant 1 each of said cams being connected in the hereinafter described manner with a pinion 34 in mesh with rack teeth 132 of the cooperating quadrant 1. Each cam 30, 31, 32, 33 includes a number of adjacent sections 30.1, 30.2, 30.3 . . . solid with each other and each cooperating with a change coin distributor as hereinafter described. Each 15 of said sections 30.1, 30.2 . . . has on its periphery recesses 30' and teeth 30' in accordance with the operation it must produce in the several respective distributors.

On a shaft 35 mounted to oscillate in the 20 register bed frame 12 a frame is fast which includes side arms 36 and a transverse spindle 37 parallel with spindle 29 and fast in arms 36. One of said arms 36 has a fork 36' having end rollers 38, 38' and actuated by a cam 39 and a counter- 25 cam 39' solid with cam shaft 28 of the cash register at a lagging angle with respect to cams 120, 121 which cause the oscillation of quadrants 15 and, generally speaking, to the cams carrying out the conventional and well known operation 30 of the cash register.

Parallel levers 40 are fulcrumed on spindle 37 each of them lying in the plane of one of the sections of a cam 30, 31, 32, 33; with each of these cams cooperates a number of levers 40 equal to 35 number of sections of such cam and each lever 40 has a nose 40' in register with respective cam section.

Springs 41 acting between a bar 42 fast in the ends of arms 36 and heels 40'' of respective levers 40 act, when the frame 36—37 is rocked, to hold noses 40' of said levers 40 against the cooperating sections of respective cams 30—33, while opposed arms of levers 40 normally abut on a stationary transverse bar 124.

Each lever 40 has a pin 43 at its end remote from nose 40' said pin 43 being able to engage a hook 44' of a rod 44 mounted to move longitudinally by means of its slots 45, 46 and supporting means therefor as hereinafter described.

The first one 45 of said slots is engaged by a pin 47 of an arm of a lever 48 solid with a shaft 49 and whose opposed arm 48' (Figure 4) actuates a rod 50 which operates a change coin distributor as hereinafter described. The other slot 46 of 55 rod 44 is arranged to slide on a guiding control pin 51 carried by a fork arm 52 which is fulcrumed on spindle 53 and whose opposite ends are actuated in the hereinafter described manner by a cam member 54 pertaining to the hereinbefore defined "denomination means" (each including a cam and a countercam as shown by 54 and 54' in respect of one of them in Figures 1 and 2). Each rod 44 is able to oscillate around pin 47 under the action of arm 52 and pin 51 and said 60 rod 44 is engaged by its hook 44' with pin 43 of lever 40 or is released therefrom in accordance with the position imparted to its cooperating arm 52 by cam member 54 and associate parts.

On its edge remote from hook 44' each rod 44 65 has a notch 44'' able to engage a stationary bar 58 when said rod 44 is shifted away from its cooperating pin 43 due to the operation of the respective arm 52. Said bar 58 thus locks rods 44 against any undue movement when they are 70 made inoperative.

The several twin cam members 54, 54' provide in their whole a single cam member also denoted by 54, they being all solid with a shaft 55 having a pinion 56 solid therewith. Said pinion 56 is driven by a quadrant 1.R which, as stated, is 5 similar to quadrants 1 and is controlled by keys 57 corresponding with several moneys or denominations of the monetary system to which the register is devoted and in respect to each of which the change is to be delivered.

Therefore, after one of the keys 57 cooperating with quadrant 1.R has been manipulated at the time of operating the cash register, said quadrant 1.R and pinion 56 move through a certain angle during the register operation and when the oscillation of quadrant 1.R is completed and before the change delivering mechanism is operated by cams 39, 39' of shaft 28 and parts 40, 44 and associated ones, said cam member 54 has taken a position corresponding with the tendered money 20 or denomination in respect to which said mechanism is required to deliver the change as the difference between such tendered money and the amount to be cashed or collected this amount having been set in the cash register by the operation of quadrants 1 under manipulation of setting keys 25 and actuation of cam shaft 28.

By the described operation, when cams 39, 39' cause the frame 36, 37 to oscillate during the register operation, levers 40 are moved with their 30 noses 40' against cooperating sections of cams 30, 31, 32, 33 and those of said levers 40 whose noses 40' engage a projecting portion (as 30') of the cooperating section of cams 30, 31, 32, 33, are caused to oscillate around spindle 37 thus 35 producing an upward stroke (Fig. 1) of the cooperating rods 44 in respect of such rods which have not been released by the respective arms 52 from cooperating pins 43. On the contrary, those of said levers 40 whose noses 40' find recesses (as 40 30') in the respective sections of cam 30, 31, 32, 33 leave their rods 44 inoperative even if the cooperating arms 52 have left said rods 44 engaged with respective levers 40 by pins 43.

Thus each change coin distributor 45 described is caused to operate only when it has been left in operative condition by the cooperating section of cam 54 and has been actually operated by the respective section of cams 30, 31, 32, 33.

Each change coin distributor (Figures 5, 6, 7) includes a tubular magazine 59 having a supply hopper 60 and a detent device actuated by a rod 50 and a two-armed crank lever 62 connected therewith and acted on by a return spring 125. Said detent device is intended to cause a coin to fall from its magazine into a delivery cup 179 at each operation and includes an ejector 61 operated by said lever 62 the hub 64 of this lever being loose on a concentric sleeve 65 and on a 60 central spindle 66 carrying it.

Each shaft 49 is provided with an actuating knob 67 located at the outside of the cash register and which provides for ejecting by hand coins from the respective magazine into cup 179 65 when desired.

Each magazine 59 is provided with an indicator intended to notify the operator when such magazine is empty or nearly so. Said indicator includes an arm 68 pivoted at 69 adjacent the 70 supply hopper 60 of the magazine 59 and able to project thereinto, it further having a signalling disk 70.

A spring 71 attached to the machine frame bed at 72 and to the arm 68 holds this arm 68 in the 75

position it has been moved into, said spring 71 being arranged to be thrown from either side to the opposite one with respect to the axis of pivot 69 due to the oscillation of arm 68.

5 The indicator 68, 70 is actuated by a reciprocating rod 73 pivotally connected with arm 14 fast to the sleeve 65 loose on spindle 66 and within the hub 64 of the ejector actuating lever 62. Said arm 14 has a finger 75 which is able to enter 10 the cooperating magazine 59 through a slot 16 and is gently pushed against the coins lying at the bottom of the magazine by a spring 77 located in an opening 78 of finger 75 and abutting on a lug 79 of hub 64 of the ejector lever 62.

15 Said lug 79 enters the opening 78 while providing for the free respective oscillation of finger 75 and lever 62.

At each operation of rod 50, the lever 62 is oscillated and ejects a coin by ejector 61, the finger 20 75 being moved by lug 79 through spring 77 towards the coins existing in the magazine and being prevented by these coins from oscillating to actuate rod 73 and indicator 68, 70 while the lever 62 and lug 79 thereof may freely oscillate 25 as permitted by the spring 77 intermediate said finger 75 and lug 79. On the return stroke of lever 62 said finger 75 is moved away from coins within magazine 59 by lug 79 engaged in its slot 18 for the unrestricted and free down motion of 30 coins in the magazine.

At the time of the delivery of the last coin or of one of last coins from magazine 59, the finger 35 75 being not longer restricted by said coins freely enters the magazine through slot 16 under the action of lever 62, lug 79 and spring 77, and by the intermediary of the rod 73 it causes the indicator 68, 70 to suddenly pass into its operative position (as shown by way of example in connection with the magazine illustrated at right hand 40 in Figure 6) to obstruct the hopper 60 and hold the indicator 70 in a position to be well in view to operator. At the time of filling the magazine again with coins the operator acts by hand an arm 68 and carries it again into its inoperative 45 position in which it is resiliently held by spring 71.

The organization of the change coin magazines and of the respective actuating cam members 30, 31, 32, 33 is made having in mind the monetary system, the change delivering apparatus and the 50 cooperating cash register are devoted to and the requirements said parts must comply with in view of said monetary system to provide for any combination as required to distribute any sum less than or, as a maximum, equal to the value of 55 the highest denomination or money which may be tendered. The cam 54 controlled by the keys 57 for setting the tendered denomination is organized in such a manner as to put in operative conditions such change coil distributors as necessary to deliver in their whole a sum equal to the value of the tendered money or denomination.

Figure 3 illustrates the organization of the several cam sections in connection with a decimal monetary system including moneys or denominations having respectively the values 0.05, 0.10, 0.20, 0.50, of unity or 1, 2, 5, 10, 20, 50 unity or unities, and assuming the cash register is built for dealing with transactions up to 99.95 unities with variations through 0.05 each. Further it is assumed that the change is to be distributed by automatic operation by coins of above denominations up to 20 unities inclusive each and up to a maximum total amount of 50 unities, changes involving more than 50 unities being assumed to

be completed by hand by the cash register operator by means of moneys of 50, 100 etc. unities. Of course the above stated values and conditions are taken as an example of a set of actual conditions of use, but the range of the apparatus operation may be extended as desired and it may include automatic distributors dealing with metal coins or notes of 50 and 100 unities each and over, and thus the apparatus may be organized for automatically distributing changes up to 100, 500 10 unities and over.

The set A (Figure 3) of keys 25.1, 25.2, 25.3, 25.4 illustrates the usual setting in keys of cash registers that is the keys devoted to set in the sum to be collected. In view of the above assumption as to ranges of the apparatus, this set includes nine keys from 1 to 9 (as 25.1, 25.2 and 25.3) in each column or ordinal place of tens, units and tenths, and a single key 25.4 in the ordinal place of hundredths that is a key 25.4 for 20 the amount 0.05 which is the single one commonly used in trade in respect of such hundredths.

The row B of keys 57 is devoted to set in the value of the tendered money with respect to which a change is to be delivered, that is it includes a key 25 for each of values 0.10, 0.20, 0.50, 1, 2, 5, 10, 20, 50, no key being provided for 0.05 coins because no change may be required in respect of such coins under the above stated practical conditions of 30 trade.

In Figure 3 section I illustrates diagrammatically the configuration and position of cams 30, 31, 32, 33 corresponding with quadrants 1 of the cash register devoted respectively to ordinal places of tens, units, tenths and hundredths 35 (the last one being restricted to the value 0.05 as above stated) assuming that all said quadrants 1 are at their zero-position. Said cams are divided each in sections as hereinbefore described their hatched portions illustrating in each section a 40 projecting portion (as 30') able to provide conditions for actuation of a cooperating change coin distributor while un-hatched portions illustrate recessed portions (30°) which are inoperative 45 with respect to said distributors. Numerals 0 . . . 9 marked in Fig. 3.I along the side of respective cams denote their portions which are carried in position for cooperation with noses 40' of cooperating levers 40 when the respective 50 quadrants (1) are positioned in the usual operation of the cash register to set in amounts including numerals 0 . . . 9 in respective columns or ordinal places.

Figure 3.II illustrates the arrangement of the 55 sections of cam 54 corresponding with keys 57 intended to be manipulated in accordance with the tendered money and providing the essential part of the hereinbefore mentioned "denomination means". It is assumed that quadrant 1.R 60 cooperating with said keys 57 is in its zero-position and hatched portions denote the operative portions of cam sections 54 (such sections being herein illustrated separately and identified by 54.1, . . . 54.9) which provide for the operation of cooperating change coin distributors by leaving rods 44 coupled with levers 40. Un-hatched portions denote the portions of said cam sections 54.1 . . . 54.9 which actuate the cooperating arms 52 to release rods 44 from levers 40 70 and put the respective change coin distributors into inoperative conditions.

The change coin distributors (as 59 and cooperating parts) are divided in a number of groups 75

equal to the number of cash setting quadrants 1 in the cash register (that is in four groups in the described embodiment) and each of said groups includes distributors of coins whose denominations belong to the ordinal of the respective quadrant, having in mind that in respect of each of certain denominations two or more magazines and distributors may be provided, they operating independently from each other under the action of separate sections of respective cam. Each of said groups is actuated by a respective cam member 30, 31, 32, 33 and each of these cam members 30, 31, 32, 33 includes a number of sections equal to the number of distributors 15 pertaining to such cam member.

More particularly, the cam 30 cooperating with quadrant 1 of tens includes three sections 30.1, 30.2, 30.3 adapted to actuate three respective distributors of coins of tens ordinal (one for 20 coins and two for 10 coins); cam 31 cooperates with units quadrant and has four sections 31.1, 31.2, 31.3, 31.4 actuating four distributors of coins belonging to units ordinal (one for 5 coins, one for 2 coins and two for 1 coin); cam 32 corresponds with tenths quadrant and has four sections 32.1, 32.2, 32.3, 32.4 which operate respectively four distributors of coins belonging to tenths ordinal (one for 0.50 coins, one for 0.20 coins and two for 0.10 coins); finally cam 33 cooperates with hundredths quadrant and has two sections each operating a distributor of coins of hundredths ordinal (two distributors for 0.05 coins).

Quadrants 1 and 1.R above referred to are not illustrated separately in detail each of them being identical with quadrant 1 illustrated in Figure 1 and having teeth as 132 meshing with one of pinions 34 and 56, respectively, illustrated in Figure 2 in connection with cam members 30, 31, 32, 33 and shaft 55 having cam member 54 fast thereto.

The distributors of each group may deliver any combination of unities of the respective ordinals up to nine unities (inclusive) in respect of intermediate ordinals and to ten unities (inclusive) for the lowest ordinal (values in this lowest ordinal being as above stated restricted to that of practical use in the same); in the highest ordinal all combinations are provided for up to the value of the highest value coin from which the automatic change delivery may be preset, less one.

Thus in the illustrated construction the following maximum total amounts may be obtained in the respective ordinals or columns: hundredth ordinal up to 10/100 (0.05+0.05); tenth ordinal up to 9/10 (0.50+0.20+0.10+0.10); unit ordinal up to 9 units (5+2+1+1); ten ordinal up to four tens (20+10+10) because as stated the automatic change delivery may be preset in respect of moneys of 5 tens but the group of this ordinal does not include a distributor of money of 5 tens they being assumed to be delivered by hand.

The unit of which the distributors of tenth, unit and ten ordinals are short is intended to be delivered by groups of lower ordinal and thus any group of distributors of a given ordinal together with the distributors of lower ordinal may deliver a full amount of 10 unities of said given ordinal. Thus the group of tenths with the group of hundredths gives 0.90+0.10=1; the group of units with groups of tenths and hundredths gives 9+0.90+0.10=10; the group of tens with those of units, tenths and hundredths gives

As above intimated, amounts over that which the apparatus is able to automatically deliver, are completed by money delivered by hand.

Each cam 30, 31, 32, 33 has such a configuration as in the several positions it may be carried into by its operating quadrant 1, that is in respect of several amounts to be collected which may be set in the machine, it causes the delivery of the difference between the figure of such amount to be collected as set in unto said quadrant and the maximum total change the group of distributors of the same ordinal (respectively 40, 9, 0.90, 0.10) may deliver. The total of such differences is obviously the correct change to be delivered. By way of example, assuming that an amount of 14.25 is to be collected, the several quadrants 1 of the cash register at the time of the usual manipulation and operation of said register will set in the respective ordinals or quadrants 1 the figures 10, 4, 0.20, 0.05 (total 14.25) and the cams 30, 31, 32, 33 will have in front of noses 40' of levers 40 their portions which in Figure 3.I are respectively in register with lines 1, 4, 2, 5. Assuming that all rods 44 are connected with respective levers 40 said cams 30-33 at the time of the described operation will cause in the respective ordinals the delivery of the above stated differences, that is 40-10=30 (made up of 20+10); 9-4=5; 0.90-0.20=0.70 (made of 0.50+0.20) and 0.10-0.05=0.05; as a total 30+5+0.70+0.05=35.75 which is the correct change over 14.25 to 50.

The several operative positions of the cam 54 setting in the value of the tendered money with respect to which money the described device is intended to deliver a change over an amount to be collected, or to deliver a change made up of coins of smaller denominations are shown by 0, 0.10, 0.20, 0.50, 1, 2, 5, 10, 20, 50 in Figure 3.II and are such as in each of them said cam 54 by means of its integral sections 54.1 . . . 54.9 (Fig. 3.II) brings in operative conditions such a number of distributors, beginning from those of lowest denomination, as required to deliver a total maximum amount equal to the denomination of the tendered money. By way of example, when a 20 coin is tendered, the distributors of 0.05, 0.05, 0.10, 0.10, 0.20, 0.50, 1, 1, 2, 5, 10, that is 20 as a total, are in operative conditions, while one of distributors of 10 coins and the distributor of 20 coins are made inoperative. In the event of the above suggested collection of 14.25 against a tendered sum of 20, the described device causes the delivery of coins only from those of the several distributors which have been put by cam 54 in operative conditions and which are actually operated by cams 30-33 through the respective levers 40 (that is 5+0.50+0.20+0.05=5.75 which is the change over 14.25 to 20) while no coin is delivered by the distributors which are in inoperative conditions (20 coin and 10 coin).

When cam 54 is in its position marked 50 in Fig. 3.II with respect to levers 52 controlled thereby, all the distributors are in operative conditions through their respective rods 44 being coupled with levers 40. On the contrary, when said cam 54 is in 0.0 position all rods 44 are released from levers 40 and therefore all distributors are inoperative to deliver coins.

Of course, when the device is manipulated in accordance with a tendered sum but no cash is set in for collection (that is none of keys 25 has been manipulated), at the time the cash register is operated the described device will deliver the change in respect of a 0 collection, that is it will

deliver the change of the tendered money or, in other words, the same amount as such tendered money, but made up of a number of coins of smaller denominations.

5 By means of the above described device the change is delivered in a maximum number of coins of smallest denomination. In some occurrences this fact may be objectionable because in practice the change against tendered money is 10 usually delivered by the minimum number of coins of the highest denomination as practicable.

To secure such a result it is necessary that when in the amount making up the change to be delivered there are one or more 0 at the right of

15 the first significant figure (that is a figure being not 0) beginning from right hand, no coin is delivered in the ordinals in which said 0 appears or appear, and that the full amount to be delivered is made up with coins of higher ordinals 20 or denominations. Assuming that the sum of 20 is tendered and the amount of 6 is to be collected, the change, that is 14.00, includes two 0 at the right of first significant figure from right (4), such 0 belonging to ordinals of tenths and hundredths. Assuming the device to operate as above described, the change would be delivered by the following series of coins:

$$10+2+1+(0.50+0.20+0.10+0.10+0.05+0.05)=14.00$$

30 to secure the lastly stated conditions, on the contrary, it is necessary that in lieu of coins belonging to tenth and hundredth ordinals (which are above written between brackets and give 1 as a total) an equal amount is delivered by a money of higher consideration that is a money of unit ordinal. In other words the delivered change must be made of the following moneys:

$$40 \quad 10+2+1+1=14.$$

45 For such a purpose it is necessary that in the operation of the device the cams 32 and 33 of tenths and hundredths are carried in such a position as to leave the respective distributors inoperative, and the cam 31 of units must be carried in a position to deliver one unity over the number of unities it should deliver in view of the figure which has been set in its cooperating quadrant 1 by the respective key 25.

50 Such a condition is secured as hereinafter described by means causing such cams to move forward through one step as required for the above stated purpose bearing in mind that, generally speaking, those of said cams 30—33 which pertain to the ordinal of the first significant figure from right and to the lower ordinals are required to move forward through one step.

55 As above exemplified, cam 31 must move (Fig. 3.I) from 6-position to 5-position (having in mind that the marking of these positions corresponds with the amount to be collected) in order to deliver 4 unities instead of 3, and the two cams 32 and 33 must move from 0-position to 60 9-position in which they cause no delivery of change coins. On the contrary the position of cam 30 must be unaffected.

65 When in the change amount there are zeroes at the left of a significant figure, the cams 30—33 of the ordinals in which said 0 appear and the cams of the ordinals higher than that of said significant figure are not to move forward. Say in the case a change involving the delivery of 10.50 (as the difference over a cash of 9.50 to be collected to a tendered sum of 20) assum-

70 ing the device is operated in the first above described manner the change would consist of $10+0.20+0.10+0.10+0.05+0.05=10.50$

To obtain the change by the minimum number of higher coins, the cam 33 (hundredth ordinal) is 5 required to be moved forward through one step to make the distributors for 0.05 and 0.05 coins inoperative, and also the cam 32 (tenth ordinal) is to be advanced through one step to deliver one tenth more to cover lack of delivery of ten 10 hundredths. Cams 30 (tens) and 31 (units) are not required to move forward they being in correct position. Then the change is delivered as follows: $10+0.50=10.50$.

15 To secure the described operation the apparatus comprises a transfer gear operative on cams 30, 31, 32, 33 which in the described embodiment operates as follows: when cam 33 is in its 0 position it causes cams 32 and 33 to move forward through one step; when cams 32 and 33 are in 20 0 position it causes cams 31, 32, 33 to move forward through one step, and when cams 31, 32 and 33 are in 0 position, it causes cams 30, 31, 32, 33 to move forward through one step.

25 The apparatus further includes a control device able to cut off at will the operation of the above stated transfer device in order to obtain the delivery of the change coins to be made in a series of coins of lower denomination, that is as firstly above described. Such a control device is actuated by a so-called change key as shown by 89 and intended to be manipulated by the operator when he desires to deliver the change of a tendered money and also, if and when desires, to deliver a change made up of a large 35 number of coins of low denominations.

30 This provision in respect of a change key is necessary because in view of above described construction and operation, when the change delivering apparatus is operated without the operator having previously set in an amount to be collected by the manipulation of keys 25 (that is when all quadrants 1 corresponding with the amount to be collected are in their 0 position) and the said tens transfer device is left operative, all the cams 30, 31, 32, 33 are in their 9-position (Figure 3.I) they thus making all the coin distributors inoperative. On the other hand such a change delivery operation without a cash to be collected being set in the register has no meaning because all existing key-operated cash registers include a locking device which makes the cash register inoperative when no amount to be collected has been set in, as well as a change key which releases said locking device to provide 45 for manipulations directed to deliver the change of money. In the embodiment of the apparatus of this invention in usual cash registers such an existing change key is availed of to cut off the operation of the tens transfer device above referred to in respect of cams 30, 31, 32, 33 when the cash register is to be operated in respect of a money change operation without any cash collection.

40 To secure the above described operation each 65 of cams 30, 31, 32, 33 actuating the coin distributors instead of being fast to its pinion 34 actuated by the respective setting in quadrant 1 and key 25, is loose on a hub 34' of said pinion 34 which in turn is loose on spindle 29 (Figures 1 and 8-11) and each of said cams 30—33 is angularly connected with the respective pinion and hub 34, 34' in such a manner as to be free 70 to move temporarily through one angular step 75

- with respect to it (said step being the angle included between two subsequent positions marked 0, 1 . . . 9 in Fig. 3.I). Such a lost motion connection is provided by a pin 80 fast on each hub 34' and entering a quadrant shaped recess 81 of the respective cams 30, 31, 32, 33 while a spring 82 operative intermediate the pin 80 and the opposite front face of recess 81 tends to hold said cam in its angular position with respect to pinion 34 and cooperating quadrant 1, in which such cam takes the positions illustrated in Fig. 3.I in respect of similar positions imparted to its quadrant 1 by the manipulation of the respective key 25.
- 15 Each cam 30-33 is further fast with a ratchet pinion 83 having ten saw teeth and cooperating with a pawl 84 which is actuated in the herein-after described manner. Said cooperating pawl 84 and ratchet pinion 83 when so actuated cause 20 the respective one of cams 30-33 to move forward through one step with respect to respective driving pinion 34 and bring such cam into a position corresponding with a completed transfer through one unity from each cam unto the 25 adjacent one of a higher ordinal.
- Each of pinions 34 actuating the lower ordinal cams 31, 32, 33 is solid with a disk 88 loosely contacting with an arm 87, 87', 87'' solid with a sleeve 85, 85', 85'' loose on a spindle 86 mounted 30 and actuated as hereinafter described. The sleeve 85'' corresponding with the cam 33 of lowest ordinal is solid with two pawls 84 actuating the ratchet pinions 83 of cams 33 and 32, the second sleeve 85' is solid with pawl 84 actuating 35 the ratchet pinion 83 of cam 31, and the third sleeve 85 is solid with pawl 84 actuating the ratchet pinion 83 of cam 30. Said disks 88 have such a diameter as to hold the respective arms 87 in a lifted position in which they hold their 40 respective pawls 84 out of engagement with respect to respective ratchet pinions 83, but each of said disks has a depression 88' in such an angular position as when the cooperating driving pinion 34 is in the position it has when cooperating quadrant 1 is in zero-position said depression 88' is in register with arm 87 to enable it to move down thus bringing the pawl or pawls 45 84 fast therewith into engagement with respective ratchet pinion or pinions 83.
- 50 The two sleeves 85' and 85 of higher ordinals have each an arm 89 which may be engaged by a pin 90 to lift pawl 84 and remove it from ratchet pinion 83, said pin 90 being fast on hub 85' or 85'' of the lower ordinal, while springs 91 act to 55 return sleeves 85, 85', 85'' with their arms 87 and pawls 84 towards disks 88 and ratchet pinions 83.
- The spindle 86 supporting the sleeves 85, 85', 60 85'' of several pawls 84 and arms 87 has its ends fast on plates 92 solid with a hub 123 loose on stub shaft 35 fastened in the cash register frame bed; plates 92 also carry a bar 94 on which return springs 91 for said pawls abut. The frame 65 consisting of hub 123, plates 92 and spindle 86 may thus oscillate around stub shaft 35 and is actuated by a cam 95 and a counter-cam 95' of the general cam shaft 28 by the intermedium of a fork arm 96 loose on shaft 35 and having rollers 97, 97' cooperating with said cams 95, 95'.
- 70 The interconnection of arm 96 with frame 92, 86 is provided, under the control of the operating key 99 (this corresponding with the "change-key" above referred to) by a gear including a lever 100 fulcrumed at 101 and actuated by said 75 key 99, a bar 102 and a lever 103 pivotally con-

nected with said bar 102 and loose on spindle 98 carried by one of said plates 92; said lever 103 has a pin 104 able to engage a notch 105 of arm 96 and it also has a notch 106 adapted to engage a pin 107 fast on the register frame bed in order to lock lever 103 with its pin 104 out of engagement with arm 96.

When key 99 is not manipulated, the frame 92, 86 and arm 96 are interengaged and then cams 95, 95' on being driven into revolution by 10 the cam shaft 28 in the general operation of the cash register cause said frame 92, 86 to oscillate; on the contrary, when key 99 is manipulated said arm 96 is held released from frame 92, 86 and therefore said frame is not oscillated in spite of 15 the arm 96 being actuated whenever the cam shaft 28 is revolved, that is at each complete operation of the cash register.

The cams 120, 121 which produce the oscillations of quadrants 1 and 1.R (whose angular 20 strokes corresponding respectively with the cash set in by keys 25 for collection and the tendered money set in by keys 57 define the positions taken by several cams 30, 31, 32, 33 and by cam 54), the cams 95, 95' actuating the arm 96 and the 25 cams 39, 39' causing the oscillation of the frame 36, 37 and therefore the operation of levers 40 which actuate the respective change coin distributors are all fastened in such a respective angular position to each other on shaft 28 as 30 when said shaft 28 is actuated through a single revolution at the time the cash register is operated under the action of a driving gear (which in the illustrated embodiment consists of an operating handle 108 and pinions 109 and 110 fast 35 on said handle and shaft 28), firstly the quadrants 15 are oscillated which carry the quadrants 1 and 1.R and therefore the cams 30, 31, 32, 33 and cam 54 in respective set up positions, then the arm 96 and frame 92, 86 are oscillated as 40 assuming that the parts 99-104 are in conditions to interconnect arm 96 and frame 92, 86 and finally the frame 36, 37 is oscillated it driving levers 40 with their noses 40' against cooperating cams 30-33 for the operation of the change coin 45 distributors 61.

Then, if the change key 99 has not been manipulated, immediately before the cooperation of levers 40 with cams 30-33 the pawls 84 cause those of cams 30-33 pertaining to the ordinal 50 in which the significant figure of lowest ordinal in the sum to be collected has been set in and to all lower ordinals to move forward through a step while the arm 87 cooperating with disc 88 of pinion 34 which has been actuated by the particular quadrant 1 in which the significant figure of lowest ordinal has been set in is lifted and makes its own pawl 84 inoperative (this pawl acting on the ratchet wheel 83 of the cam of the immediately higher ordinal) as well as, in view 60 of the parts 90, 89, the pawls 84 of all the cams of higher ordinals even if in such higher ordinals one or more disks 88 are in 0 position (as above defined in the description of operation of parts 88, 88', 87 and related ones) thus effecting 65 a transfer in the above stated meaning.

In the above stated conditions the described operation is secured and then cams 30-33 of lower ordinals with respect to that on which the lowest ordinal figure has been set in are inoperative with respect to their distributors whilst said cam on which the lowest ordinal significant figure has been set in is moved forward through one step to compensate for the cams of lower ordinals having been made inoperative; as above de- 75

scribed the higher ordinal cams are held in the position they have taken by effect of the operation of respective quadrant 1 and cooperating keys 25.

- 5 On the contrary, all pawls 84 are left inoperative if the change key 99 has been manipulated. As to the cash register operation, assuming all magazines 59 contain a supply of coins of respective denominations, keys 25 of the cash register 10 are manipulated in the usual manner in accordance with the amount to be collected, that of keys 57 corresponding with tendered money is actuated and the main shaft 28 of the register is driven by means of handle 108 (a suitable motor 15 for being used in lieu of said handle if desired) to cause the said shaft 28 to rotate through a single full revolution it thereafter coming again at rest, as usual in cash registers.

Assuming the item 15.25 has been set in by 20 keys 25 and that a 50 coin is being tendered and the respective key 57 has been manipulated, and further assuming that the change key 99 has not been operated, quadrants 1, 1.R on carrying out their operation cause the cams 30, 31, 32, 33 to 25 take the respective positions in which their portions 1, 5, 2, 5 (Fig. 3.I) are in register with noses 40' of levers 40, while the cam 54 takes its 50-position (Fig. 3.II) in which it leaves all the rods 44 coupled with respective levers 40, and all 30 pawls 84 are made inoperative; at the time the cams 39-39' actuate the frame 36, 37 said levers 40 are driven with their noses 40' against cams 30-33 and those are operated amongst them whose noses 40' have a projecting portion 35 (as 30') in front of, while levers 40 are left inoperative whose noses 40' have recessed portions as 30' of cams 31-33 in front of; thus such distributors as 61 as necessary to deliver the correct change (34.75) are actuated.

40 In the event that a money having a lower denomination than the maximum one for which the apparatus is organized is tendered, the cam 54 in view of the manipulation of the respective key 57 causes the levers 40 of a number of distributors to be released from rods 44 such distributors 45 thus being left inoperative during the operation.

Finally, if the change key 99 has been operated, all pawls 84 are left inoperative and the change is delivered in a larger number of small 50 denomination coins.

50 If desired, the delivery of coins may be produced from desired magazines by manipulating the respective handles 67 and the signalling device 68, 70 is made automatically operative in 55 respect of magazines 59 as soon as they are empty as described with reference to Figures 6 and 7.

The apparatus of this invention has been described in combination with a cash register and 60 assuming it is actuated by setting in parts of such a register, but this apparatus may be actuated by the parts of a totalizing apparatus, the several pinions 34 which actuate cams 30, 31, 32, 33 . . . being then driven by respective pinions 65 solid with parts of said totalizing apparatus in lieu of the setting quadrants of a cash register; then the change or difference will be delivered in respect to the sum totalized by said totalizing apparatus instead of being delivered with respect 70 to a denomination set in the cash register at each separate operation.

Of course, instead of using cam members as 30-33 arranged and actuated as described, the apparatus may include cam members or equivalent means arranged directly on quadrants 1, 75

1.R or also reciprocating members having cam portions.

Finally, the described device may be provided by itself with separate setting in means and actuating means in order to be used independently 5 of other machines.

I claim:

1. Apparatus for computing and delivering change from tendered money over variable amounts to be collected, comprising change coin 10 distributors grouped in sets each devoted to one ordinal of the maximum amount for which the apparatus is designed and each including a magazine and an ejector, means for actuating said distributor ejectors, denomination means having 15 selective control parts and shiftable in accordance with several money denominations, means for positioning said denomination means in accordance with the denomination of the money tendered, means under the control of said denomination means selective control parts for selectively disabling said distributor ejector actuating means, shiftable change computing members each devoted to one ordinal of the maximum amount for which the apparatus is designed and 20 including sections each cooperative with said ejector actuating means of one of the distributors of that of said distributor sets devoted to the same ordinal, said sections having in differentiated regions thereof configurations conditioning 25 for selective actuations of said respective change coin distributor ejector actuating means accounting for several digits in said ordinal, means for positioning each change computing member with a selected region thereof in condition for co-operation with respective distributor ejector actuating means in accordance with the digit the particular amount to be collected includes in the respective ordinal, and means causing the cooperation of said change coin distributor ejector 30 actuating means and respective change computing members for the selective drive of said change coin distributor ejector actuating means.

2. Apparatus for computing and delivering change from tendered money over variable 45 amounts to be collected, comprising change coin distributors grouped in sets each devoted to one ordinal of the maximum amount for which the apparatus is designed and each including a magazine and an ejector, means for operating said

distributor ejectors, denomination means having selective control parts and shiftable in accordance with several money denominations, means for positioning said denomination means in accordance with the denomination of the 50 money tendered, shiftable change computing members each devoted to one ordinal of the maximum amount for which the apparatus is designed and including sections each in respect to one of the distributors of that of said distributor sets devoted to the same ordinal, said sections having in differentiated regions thereof configurations conditioning for selective actuations of said respective operating means and change coin distributor ejectors accounting for 55 several digits in said ordinal, driving members for said distributor ejector operating means adapted to cooperate at each operation of the apparatus with said change computing member sections, means for positioning each change computing member with a selected region thereof in 60 condition for cooperation with said driving members in accordance with the digit the particular amount to be collected includes in the respective ordinal, transmission means capable of being dis- 70

- abled intermediate said driving members and respective distributor ejector operating means, means under the control of said denomination means selective control parts for selective control of said transmission means, and means causing the cooperation of said driving members and respective change computing members for the selective drive of said change coin distributor ejector operating means.
- 5 3. Apparatus for computing and delivering change from tendered money over variable amounts to be collected, comprising change coin distributors grouped in sets each devoted to one ordinal of the maximum amount for which the apparatus is designed and each including a magazine and an ejector, means for operating said distributor ejectors, a denomination member having control parts in selective angularly differentiated portions of its periphery and angularly shiftable in accordance with several money denominations, means for angularly positioning said denomination member in accordance with the denomination of the money tendered, shiftable change computing members each devoted 10 to one ordinal of the maximum amount for which the apparatus is designed and including sections each in respect to one of the distributors of that of said distributor sets devoted to the same ordinal, said sections having in differentiated regions thereof configurations conditioning for a selective actuation of said respective operating means and change coin distributor ejectors accounting for several digits in said ordinal, driving members for said distributor ejector operating means adapted to cooperate at each operation of the apparatus with said change computing member sections, means for positioning each computing member with a selected region thereof in condition for cooperation with said driving members in accordance with the digit the particular amount to be collected includes in the respective ordinal, transmission means capable of being disabled intermediate said driving members and respective distributor ejector operating means, means under the control of said denomination member control parts for selective control of said transmission means, and means causing the cooperation of said driving members and respective change computing members for the selective drive of said change coin distributor ejector operating means.
- 15 4. Apparatus for computing and delivering change from tendered money over variable amounts to be collected, comprising change coin distributors grouped in sets each devoted to one ordinal of the maximum amount for which the apparatus is designed and each including a magazine and an ejector, means for operating said distributor ejectors, denomination means having selective control parts and shiftable in accordance with several money denominations, means for positioning said denomination means in accordance with the denomination of the money tendered, angularly shiftable change computing 20 members each devoted to one ordinal of the maximum amount for which the apparatus is designed and including sections each in respect to one of the distributors of that of said distributor sets devoted to the same ordinal, said sections having projecting and depressed portions in angularly differentiated regions of their peripheries for selective actuations of respective change coin distributor ejectors accounting for several digits in the respective ordinal, driving members 25 for said distributor ejector operating means adapted to cooperate at each operation of said apparatus with portions of said change computing member sections, means for angularly positioning each change computing member with selected peripheral regions of sections thereof in condition for cooperation with said driving members in accordance with the digit the particular amount to be collected includes in the respective ordinal, transmission means capable of being 30 disabled intermediate said driving members and respective distributor ejector operating means, means under the control of said denomination means selective control parts for selective control of said transmission means, and means causing the cooperation of said driving members and said portions of respective change computing members for the selective drive of said change coin distributor ejector operating means.
- 35 5. Apparatus for computing and delivering change from tendered money over variable amounts to be collected, comprising change coin distributors grouped in sets each devoted to one ordinal of the maximum amount for which the apparatus is designed and each including a magazine and an ejector, means for operating said distributor ejectors, denomination means having selective control parts and shiftable in accordance with several money denominations, means for positioning said denomination means in accordance with the denomination of the money tendered, angularly shiftable change computing 35 members each devoted to one ordinal of the maximum amount for which the apparatus is designed and including sections each in respect to one of the distributors of that of said distributor sets devoted to the same ordinal, said sections having projecting and depressed portions in angularly differentiated regions of their peripheries for selective actuations of respective change coin distributor ejectors accounting for several digits in the respective ordinal, driving members 40 for said distributor ejector operating means adapted to cooperate at each operation of said apparatus with portions of said change computing member sections, means for angularly positioning each change computing member with selected peripheral regions of sections thereof in condition for cooperation with said driving members in accordance with the digit the particular amount to be collected includes in the respective ordinal, transmission means capable of being 45 disabled intermediate said driving members and respective distributor ejector operating means, means under the control of said denomination means selective control parts for selective control of said transmission means, and means causing the cooperation of said driving members and said portions of respective change computing members for the selective drive of said change coin distributor ejector operating means.
- 50 6. Apparatus for computing and delivering change from tendered money over variable amounts to be collected, comprising change coin distributors grouped in sets each devoted to one ordinal of the maximum amount for which the apparatus is designed and each including a magazine and an ejector, means for operating said distributor ejectors, denomination means having selective control parts and shiftable in accordance with several money denominations, means for positioning said denomination means in accordance with the denomination of the money tendered, shiftable change computing 55 members each devoted to one ordinal of the maximum amount for which the apparatus is designed and including sections each in respect to one of the distributors of that of said distributor sets devoted to the same ordinal, said sections having projecting and depressed portions in differentiated regions thereof for selective actuations of respective change coin distributor ejectors accounting for several digits in respective ordinal, driving members for said distributor ejector operating means adapted to coop-

to one of the distributors of that of said distributor sets devoted to the same ordinal, said sections having projecting and depressed portions in differentiated regions thereof for selective actuations of respective change coin distributor ejectors accounting for several digits in the respective ordinal, driving members for said distributor ejector operating means each adapted to cooperate with one of said change computing member sections, means for positioning each change computing member with selected portions of sections thereof in condition for cooperation with said driving members in accordance with the digit the particular amount to be collected includes in the respective ordinal, a support in which said driving members are movably mounted, means to move said support and driving members towards said change computing members at each operation of said apparatus for selective operation of said driving members by said projecting portions of said change computing members, transmission means capable of being disabled intermediate said driving members and respective distributor ejector operating means, and means under the control of said denomination means selective control parts for selective control of said transmission means.

7. Apparatus for computing and delivering change from tendered money over variable amounts to be collected, comprising change coin distributors grouped in sets each devoted to one ordinal of the maximum amount for which the apparatus is designed and each including a magazine and an ejector, means for operating said distributor ejectors, denomination means having selective control parts and shiftable in accordance with several money denominations, means for positioning said denomination means in accordance with the denomination of the money tendered, angularly shiftable change computing means each devoted to one ordinal of the maximum amount for which the apparatus is designed and including sections each in respect to one of the distributors of that of said distributor sets devoted to the same ordinal, said sections having projecting and depressed portions in angularly differentiated regions of their peripheries for selective actuations of respective change coin distributor ejectors accounting for several digits in the respective ordinal, driving members for said distributor ejector operating means each adapted to cooperate with one of said change computing member sections, means for angularly positioning each change computing member with selected peripheral portions of sections thereof in condition for cooperation with said driving members in accordance with the digit the particular amount to be collected includes in the respective ordinal, a support in which said driving members are movably mounted, means to move said support and driving members toward said change computing members at each operation of said apparatus for selective operation of said driving members by said projecting portions of said change computing members, transmission means capable of being disabled intermediate said driving members and respective distributor ejector operating means, and means under the control of said denomination means selective control parts for selective control of said transmission means.

8. Apparatus for computing and delivering change from tendered money over variable amounts to be collected, comprising change coin distributors grouped in sets each devoted to one

ordinal of the maximum amount for which the apparatus is designed and each including a magazine and an ejector, means for operating said distributor ejectors, denomination means having selective control parts and shiftable in accordance with several money denominations, means for positioning said denomination means in accordance with the denomination of the money tendered, shiftable change computing means each devoted to one ordinal of the maximum amount for which the apparatus is designed and including sections each in respect to one of the distributors of that of said distributor sets devoted to the same ordinal said sections having projecting and depressed portions in differentiated regions thereof for selective actuations of respective change coin distributor ejectors accounting for several digits in the respective ordinal, arms for driving said distributor ejector operating means each adapted to cooperate with one of said change computing member sections, means for positioning each change computing member with selected portions of sections thereof in condition for cooperation with said driving arms in accordance with the digit the particular amount to be collected includes in the respective ordinal, a movable support in which said arms are pivoted, means to move said support and arms towards said change computing members at each operation of the apparatus for selective actuation of said arms by said projecting portions of said change computing members, bars each connected with said operating means of one of said distributor ejectors and adapted to cooperate with one of said arms and means on said cooperating bars and arms for their releasable coupling, said coupling means being under the control of said selective control parts of said denomination means for selectively releasing and engaging said bars and arms in accordance with the position of said denomination means.

9. Apparatus for computing and delivering change from tendered money over variable amounts to be collected, comprising change coin distributors grouped in sets each devoted to one ordinal of the maximum amount for which the apparatus is designed and each including a magazine and an ejector, means for actuating said distributor ejectors, denomination means having selective control parts and shiftable in accordance with several money denominations, means for positioning said denomination means in accordance with the denomination of the money tendered, means under the control of said denomination means selective control parts for selectively disabling said distributor ejector actuating means, shiftable change computing members each devoted to one ordinal of the maximum amount for which the apparatus is designed and including sections each cooperative with said ejector actuating means of one of the distributors of that of said distributor sets devoted to the same ordinal, said sections having projecting portions in differentiated regions thereof, means for positioning each change computing member with a selected region thereof in condition for cooperation with respective distributor ejector actuating means in accordance with the digit the particular amount to be collected includes in the respective ordinal, the lowest ordinal change computing member having a configuration causing the cooperating change coin distributor ejector actuating means to deliver change in an amount equal to the difference between one unity of the 75

- next higher ordinal and the digit to be collected in said lowest ordinal and the change computing members of ordinals other than the lowest one having a configuration causing the cooperating 5 change coin distributor ejector actuating means to deliver change in an amount equal to the difference between the maximum digit permissible in respective ordinal and the digit to be collected in such ordinal, and means causing the 10 cooperation of said change coin distributor ejector actuating means and said portions of respective change computing members for selective actuation of said distributor ejectors to deliver coins providing said change amounts.

15 10. Apparatus for computing and delivering change from tendered money over variable amounts to be collected, comprising change coin distributors grouped in sets each devoted to one ordinal of the maximum amount for which the 20 apparatus is designed and each including a magazine and an ejector, means for operating said distributor ejectors, denomination means having selective control parts and shiftable in accordance with several money denominations, 25 means for positioning said denomination means in accordance with the denomination of the money tendered, shiftable change computing members each devoted to one ordinal of the maximum amount for which the apparatus is designed and including sections each cooperative with said distributor sets devoted to the same ordinal, said sections having projecting and depressed portions in differentiated regions thereof for selective control 30 sections each in respect to one of the distributors of that of said distributor sets devoted to the same ordinal, said sections having projecting and depressed portions in differentiated regions thereof for selective control 35 of the ejectors of respective change coin distributors accounting for several digits in the respective ordinal, driving members for said distributor ejector operating means adapted to cooperate with portions of said change computing 40 member sections, means for positioning each change computing member with selected regions of sections thereof in condition for cooperation with said driving members in accordance with the digit the particular amount to be collected 45 includes in the respective ordinal, the lowest ordinal change computing member having a configuration causing the cooperating change coin distributor ejector actuating means to deliver change in an amount equal to the difference between one unity of the next higher ordinal and the digit to be collected in said lowest ordinal and the change computing members of the ordinals other than the lowest one having a configuration causing the cooperating change coin distributor 50 ejector actuating means to deliver change in an amount equal to the difference between the maximum digit permissible in the respective ordinal and the digit to be collected in such ordinal, transmission means capable of being disabled intermediate said driving members and respective distributor ejector operating means, means under the control of said denomination means selective control parts for selective control of said transmission means, and means causing the cooperation of said driving members and said portions of respective change computing members for the selective drive of said change coin distributor 55 ejector operating means.

60 11. Apparatus for computing and delivering change from tendered money over variable amounts to be collected, comprising change coin distributors grouped in sets each devoted to one ordinal of the maximum amount for which the apparatus is designed and each including a magazine and an ejector, means for actuating said 65 distributor ejectors, denomination means having selective control parts and shiftable in accordance with several money denominations, means for positioning said denomination means in accordance with the denomination of the money tendered, means under the control of said denomination means selective control parts for selectively disabling said distributor ejector actuating means, shiftable change computing members each devoted to one ordinal of the maximum 70 75 12. Apparatus for computing and delivering change from tendered money over variable amounts to be collected, comprising change coin distributors grouped in sets each devoted to one ordinal of the maximum amount for which the apparatus is designed and each including a magazine and an ejector, means for actuating said distributor ejectors, denomination means having selective control parts and shiftable in accordance with several money denominations, means for positioning said denomination means in accordance with the denomination of the money tendered, means under the control of said denomination means selective control parts for selectively disabling said distributor ejector actuating means, shiftable change computing members each devoted to one ordinal of the maximum 75

amount for which the apparatus is designed and including sections each cooperative with said 5
ejector actuating means of one of the distributors of that of said distributor sets devoted to the
same ordinal, said sections having projecting
portions in differentiated regions thereof, means
for positioning each change computing member
with a selected region thereof in condition for
cooperation with respective distributor ejector
actuating means in accordance with the digit the
particular amount to be collected includes in the
respective ordinal, the lowest ordinal change
computing member having a configuration caus- 5
ing the cooperating change coin distributor ejec- 10
tor actuating means to deliver change in an
amount equal to the difference between one unity
of the next higher ordinal and the digit to be
collected in such lowest ordinal and the change
computing members of the ordinals other than
the lowest one having a configuration causing the
cooperating change coin distributor ejector actuating
means to deliver change in an amount equal to the difference between one unity of the next higher ordinal and the digit to be collected in such lowest ordinal and the change computing members of the ordinals other than
the lowest one having a configuration causing the
cooperating change coin distributor ejector actuating
means to deliver change in an amount equal to the difference between the maximum digit permissible in the respective ordinal and the
digit to be collected in such ordinal, means for
shifting each change computing member forward
through one step, means for making said shifting
means for the change computing members of the
lowest ordinal and of the next higher ordinal
inoperative when said lowest ordinal change
computing member is in position for delivery of
change, means for making said shifting means of
each change computing member of subsequent
higher ordinal inoperative when the change com- 30
puting member of the respective next lower ordinal
has been positioned for delivery of change,
single direction operative means coupling each
of said shifting means with that of the next
higher ordinal change computing members to
cause each of said shifting means to make said
shifting means of change computing members
of higher ordinals inoperative on it being made
inoperative, means under the operator's control to
make all said shifting means inoperative, and
means causing the cooperation of said change
coin distributor ejector actuating means and
said portions of said change computing members
for selective actuation of said distributor
ejectors to deliver coins providing said change
amounts. 50

13. Apparatus for computing and delivering
change from tendered money over variable
amounts to be collected, comprising change coin
distributors grouped in sets each devoted to one
55
ordinal of the maximum amount for which the
apparatus is designed and each including a mag-
azine and an ejector, means for actuating said
distributor ejectors, denomination means having
selective control parts and shiftable in accord-
ance with several money denominations, means
60
for positioning said denomination means in ac-
cordance with the denomination of the money
tendered, means under the control of said de-
nomination means selective control parts for se-
lectively disabling said distributor ejector actu-
ating means, shiftable change computing members
65
each devoted to one ordinal of the maximum
amount for which the apparatus is designed and
including sections each cooperative with said
ejector actuating means of one of the distributors
of that of said distributor sets devoted to the
same ordinal, said sections having projecting
portions in differentiated regions thereof, means
70
for positioning each change computing member
with a selected region thereof in condition for
cooperation with respective distributor ejector
actuating means in accordance with the digit the
particular amount to be collected includes in the
75

cooperation with respective distributor ejector
actuating means in accordance with the digit the
particular amount to be collected includes in the
respective ordinal, the lowest ordinal change
computing member having a configuration caus- 5
ing the cooperating change coin distributor ejec- 10
tor actuating means to deliver change in an
amount equal to the difference between one unity
of the next higher ordinal and the digit to be
collected in such lowest ordinal and the change
computing members of ordinals other than the
lowest one having a configuration causing the
cooperating change coin distributor ejector actuating
means to deliver change in an amount equal to the difference between the maximum 15
digit permissible in respective ordinal and the
digit to be collected in such ordinal, a one-step
lost-motion coupling between each of said position-
ing means and the cooperating change com- 20
puting member, means for shifting each of said
change computing members through said one-
step lost-motion with respect to said respective
positioning means, releasing means for making
said shifting means of the lowest ordinal change
computing member inoperative and located un- 25
der the control of its own positioning means, re-
leasing means for making said shifting means of
each of the other change computing members
inoperative and located each under the control
of said positioning means of the said change com- 30
puting member of the respectively next lower ordinal, said releasing means being made operative
by said positioning means of the respective
change computing members when such position-
ing means are in a position other than their no- 35
change position, single direction operative means
coupling each of said shifting means with that
of the next higher ordinal change computing
member to cause each of said shifting means to
make said shifting means of change computing 40
members of higher ordinals inoperative on it being
made inoperative, and means causing the
cooperation of said change coin distributor ejec-
tor actuating means and said portions of respective
change computing members for selective ac- 45
tuation of said distributor ejectors to deliver
coins providing said change amounts.

14. Apparatus for computing and delivering
change from tendered money over variable
amounts to be collected, comprising change coin 50
distributors grouped in sets each devoted to one
ordinal of the maximum amount for which the
apparatus is designed and each including a mag-
azine and an ejector, means for actuating
said distributor ejectors, denomination means 55
having selective control parts and shiftable in
accordance with several money denominations,
means for positioning said denomination means
in accordance with the denomination of the
money tendered, means under the control of said 60
denomination means selective control parts for
selectively disabling said distributor ejector actu-
ating means, shiftable change computing members
each devoted to one ordinal of the maximum
amount for which the apparatus is designed and 65
including sections each cooperative with said
ejector actuating means of one of the distribu-
tors of that of said distributor sets devoted to
the same ordinal, said sections having projecting
portions in differentiated regions thereof, means
70
for positioning each change computing member
with a selected region thereof in condition for
cooperation with respective distributor ejector
actuating means in accordance with the digit the
particular amount to be collected includes in the
75

respective ordinal, the lowest ordinal change computing member having a configuration causing the cooperating change coin distributor 5 ejector actuating means to deliver change in an amount equal to the difference between one unity of the next higher ordinal and the digit to be collected in such lowest ordinal and the other change computing members having a configuration causing the cooperating change coin distributor 10 ejector actuating means to deliver change in an amount equal to the difference between the maximum digit permissible in respective ordinal and the digit to be collected in such ordinal, a one-step lost-motion coupling 15 between each of said positioning means and the cooperating change computing member, means for shifting each of said change computing members through said one-step lost-motion with respect to said respective positioning means, releasing 20 means for making said shifting means of the lowest ordinal change computing member inoperative and located under the control of its own positioning means, releasing means for making said shifting means of each of the other change 25 computing members inoperative and located each under the control of said positioning means of the said change computing member of the respectively next lower ordinal, said releasing means being made operative by said positioning 30 means of the respective change computing members when such positioning means are in a position other than their no-change position, and single direction operative means coupling each of said shifting means with that of the next 35 higher ordinal change computing members to cause each of said shifting means to make said shifting means of change computing members of higher ordinals inoperative on it being made inoperative, means under the operator's control 40 to make all said shifting means inoperative, and means causing the cooperation of said change coin distributor ejector actuating means and said portions of respective change computing members for selective actuation of said distributor 45 ejectors to deliver coins providing said change amounts.

15. Apparatus for computing and delivering change from tendered money over variable amounts to be collected, comprising change coin 50 distributors grouped in sets each devoted to one ordinal of the maximum amount for which the

apparatus is designed and each including a magazine and an ejector, a feeler adapted to enter said magazine, means for operating each of said ejectors, spring means intermediate said feeler and respective ejector operating means, said 5 spring means acting on said feeler at each operation of said operating means to cause it to extend into said magazine, indicating means connected with said feeler and adapted to take an alarm position when said feeler deeply extends 10 into said magazine by not being restricted by coins therein, denomination means having selective control parts and shiftable in accordance with several money denominations, means for positioning said denomination means in accordance with the denomination of the money tendered, shiftable change computing means each devoted to one ordinal of the maximum amount for which the apparatus is designed and including sections each in respect to one of the distributors of that of said distributor sets devoted to the same ordinal, said sections having projecting and depressed portions in differentiated regions thereof for selective control of respective change coin distributor ejectors accounting for 20 several digits in the respective ordinal, arms for driving said ejector operating means each adapted to cooperate with one of said change computing member sections, means for positioning each change computing member with selected portions 25 of sections thereof in condition for cooperation with said driving arms in accordance with the digit the particular amount to be collected includes in the respective ordinal, a movable support in which said arms are pivoted, means to 30 move said support and arms towards said change computing members at each operation of the apparatus for selective actuation of said arms by said projecting portions of said change computing members, bars each connected with said 35 operating means of one of said ejectors and adapted to cooperate with one of said arms, and means on said cooperating bars and arms for their releasable coupling, said coupling means being under the control of said selective control 40 parts of said denomination means for selectively releasing and engaging said bars and arms in accordance with the position of said denomination means.

ATTILIO ERRERA. 50
